FIG. 1.

FIG. 2.

FIG. 3.

FIG. 4.

FIG. 5.

FIG. 6.

FIG. 7.

FIG. 8.

The characteristic features of my design reside in the solid bands of color which are shown in FIGURES 1, 2 and 4 through 7 with the top of the right-hand band shown in FIGURES 1 and 2 being interrupted by an opening through which shows a medicinal capsule secured to a backer by a transparent overlay.

I claim:

The ornamental design for a package of medicinal capsules, as shown and described.
